UNITED STATES PATENT OFFICE.

GEORGES PAILLERY, OF COURBEVOIE, FRANCE.

DESIGN FOR AN ATOMIZER.

Application filed June 4, 1927. Serial No. 22,330. Term of patent 3½ years.

To all whom it may concern:

Be it known that I, GEORGES PAILLERY, a citizen of the Republic of France, residing in the city of Courbevoie, Seine, France, have invented a new, original, and ornamental Design for Atomizer, of which the following is a specification, reference being had to the accompanying drawing, forming a part thereof.

In the drawing

Fig. 1 is a side elevation of the atomizer employed in my improved design.

Fig. 2 is a top plan view of my design.

I claim:

The ornamental design for an atomizer substantially as shown.

GEORGES PAILLERY.
